PROCESS AND APPARATUS FOR SIMULTANEOUSLY DRAWING AND PLATING WIRE

Herbert Kenmore and Walter J. Manson, Jersey City, N. J., assignors, by mesne assignments, to National Standard Company, Niles, Mich., a corporation of Delaware

Application July 13, 1951, Serial No. 236,663

3 Claims. (Cl. 204—28)

This invention relates to a process and apparatus for drawing wire and simultaneously electroplating the same.

An object of the invention is to provide an apparatus which is adapted to plate wire under the high, substantially uniform tension required to draw the wire to a smaller diameter.

Another object of the invention is to provide a process and apparatus whereby wire can be plated while held under high tension between a drawing die and a take-up block.

Another object of the invention is to provide a process and apparatus for vibrating a wire while it is being plated whereby it is possible to increase the current density (rate of deposition) of the plating operation to a degree heretofore considered impractical.

These objects and others ancillary thereto are obtained by continuously stretching a portion of a moving length of the wire between a die and a take-up block which is spaced a sufficient distance from the die to permit the addition of cleaning, rinsing, electroplating, and other required baths between said die and the take-up block. The wire is passed through these baths without contacting electrodes or guide rollers except that at one or more points the wire is struck at regular intervals to cause it to vibrate.

The tension or stress applied to the wire is equivalent to that which is sufficient to draw the wire through a die which reduces its diameter and is approximately 25—90% of the tensile strength of the wire. Other wire reducing means such as a pair of grooved rollers may be substituted for the die but it is noted that the stress applied by a die is not only of the desired degree but it is also a very uniform one. The contact with the electrodes is avoided by placing the anode and the cathode of the generator in two separate baths such as an electrolytic cleaning bath and the electroplating bath whereby the current passes from the anode in the plating bath through the said bath along the wire, and through the cleaning bath to the cathode in the said cleaning bath without direct contact between the wire and the electrodes. This idea of non-contacting electrodes is known but in this invention the idea cooperates with the other features thereof to enable the take-up block to apply a uniform high tension to the wire to draw the same through the die and the baths and to enable the vibrations induced by striking the wire to extend all through the plating bath. In order to effectively apply a vibrating force to the wire while being treated, contacts and guide rolls have to be avoided in or between the baths but guide rolls may be inserted between the die and the first bath or between the last bath and the drawing means. The same tanks can be constructed so as to electroplate a number of wires simultaneously.

The novel features characteristic of this invention are set forth with particularity in the appended claims. The invention itself, however, both as to its organization and its method of operation, together with additional objects and advantages thereof, will best be understood from the following description of specific embodiments when read in connection with the accompanying drawings in which:

Figs. 1A and 1B together form a cross sectional side view of one form of the apparatus.

Fig. 2 is a top plan view of the apparatus of Figs. 1A and 1B with some of the baths omitted.

Fig. 3 is a detail view partly in cross section of one bath with its liquid circulating system.

Fig. 4 is a detail view of a typical drawing die.

As shown in Figs. 1A, 1B and 2 the wire 100 is drawn through a die 10, and pulled through the die and the series of baths 20, 30, 40, 50, 60, 70 and 80 by take-blocks 12, 13, 14 or 15. The take-up blocks 12, 13, 14 and 15 are on a level with the outlet opening of the particular die from which they pull the wire so that the wire travels in a substantially straight horizontal path. According to the present invention the die and drawing blocks have been spaced a distance of over 30 feet, although it is obvious that the distance between the die and the drawing blocks will depend on the length of the baths through which the wire is to be passed. A guide roller or similar guide means could be inserted between the die 10 and the first bath.

A suitable sequence of baths is shown in Figs. 1A and 1B, the bath 20 being a heated electrolytic cleaning bath, bath 40 containing an acid dip, bath 60 being the electroplating bath and bath 80 being a hot water bath for drying the wire. These relatively long baths 20, 40, 60 and 80 have shorter rinsing baths 30, 50 and 70 therebetween which are continuously fed with a stream of ordinary tap water.

The various baths are constructed in such a way that the wire can be fed therethrough in a substantially straight horizontal path under tension while said wire is completely immersed in the bath liquid. As shown in Figure 3, the bath 40 has slits 41, 42 at the ends thereof which are somewhat wider than the diameter of the wire 100. Adjacent each of the slotted ends of the bath structure is a trough 43 or 44 adapted to catch the bath liquid which flows through said slits 41, 42. This overflow liquid caught in troughs 43, 44, drains into the storage tank 48 through conduits 45, 46 and from the storage tank 48 is pumped by pump 49 through conduit 47 back into the bath 40. The liquid is pumped back into bath 40 at a sufficient rate to maintain the liquid level 101 of the bath above the top surface of the wire 100. In the case of the rinsing baths 30, 50 and 70 the recirculating system can be omitted.

The other baths 30, 40, 50, 60, 70, 80, are constructed similarly to bath 40. Bath 20, for example, contains similar slits 21, 22, troughs 23, 24, drainage connections 25, 26 and supply conduit 27. Other methods of constructing the supply conduits, collecting troughs, etc., so as not to interfere with the passage of the wire through the baths and yet assure the complete submersion of the wire could be employed. Additional methods are shown in Chubb Patent No. 1,068,411 and in Presser Patent No. 1,117,240 for example. The bath 20 contains electrodes 29, 29 and the bath 60 contains electrodes 69, 69 which do not come into direct contact with the wires. The electrodes are connected to a common source of direct current 16 as shown in Figure 2.

Since the wire 100 passes from the die 10 to the guide roller 12, for example, in a substantially straight horizontal path and since the wire is under a very large tension which is great enough to draw the same, the said wire may be caused to vibrate all along the length between the die 10 and guide roller 12 by intermittently striking the same. One difficulty in plating wires is to obtain the desired rate of deposition (measured in amperes per square foot and expressed as current density, for example). The limitation on current density is determined by the speed with which the ions in the plating solution can be replaced or recreated adjacent the

cathode for deposition on the latter. The conventional way of improving this condition is by agitating the solution, by mechanically holding and vibrating the cathode or by a combination of both such means. According to this invention the plating operation is carried out while the wire is under a high constant tension sufficient to draw said wire. Heretofore it was not considered feasible to plate wire while held under the high tension required to draw the same. This invention is based on the discovery not only that such a process is feasible but that it has at least one added advantage, namely, that while under such tension the wire may be made to act as its own vibrator. The wire when struck acts like a violin string. As shown in Figs. 1A, 1B and 2, the striking mechanism 90 for causing the wire 100 to vibrate is placed between the baths 70 and 80, although it makes little difference between which two baths it is placed since the vibrations occur all along the stretched length of the wire 100 due to the fact that no electrodes, guide rollers or other means contact the wire between the die 10 and guide roller 12. The striking mechanism shown consists of a disk 91 held on rotating shaft 92. The disk 91 carries one or more fingers 93, 94 which move from a position below the line of travel of the wire 100 to a position above the line of travel so that each finger 93, 94 strikes the wire during each rotation. The shaft 92 is driven by suitable means such as pulley 95 and belt 96. The tension required to hold the wire at its entrance end so that it can be vibrated according to the invention is possible only through a device capable of deforming the wire such as the die 10, or an equivalent means. The wire could be vibrated by other devices such as by electromagnetic means, etc. By this unusual method of vibrating and agitating, the current density has been increased to many times that which is possible without such vibrating step. For example, current densities as high as 3000 amps per square foot have been employed as compared with a maximum of about 200 amps per square foot ordinarily employed. The exact nature of the die 10 is not important as long as the die is capable of holding the wire under sufficient tension. Fig. 4 shows a conventional type of die 10 having an orifice 11 which can be employed. As shown in Fig. 2 a plurality (four shown) of wires 100 may be treated simultaneously the guide rollers 12, 13, 14 and 15 and take-up rollers 16, 17, 18 and 90 being offset with respect to each other. The wire 100 can be of any suitable size and subsequent to plating, it may be redrawn to smaller diameter since the plating which is applied at a relatively high current density is very uniform and is very adherent to the base material.

The following example illustrates how the process is carried out on an actual wire although it is understood that the example does not in any way limit the scope of the invention.

Example

A .045" copper wire is drawn through a die 10 to reduce its diameter to .042" by an apparatus like that shown in Figs. 1A, 1B and 2 and drawn through a series of baths 20, 30, 40, 50, 60, 70 and 80. The speed at which the wire is pulled through the baths is from 3 to 200 feet per minute. In bath 20 the wire is cleaned with an electrolytic cleaning bath such as a bath of sodium phosphate at 180° F. In bath 30 the wire is rinsed, in bath 40 it is dipped in 10% sulfuric acid, in bath 50

it is again rinsed, in 60 the wire becomes the cathode and is plated with tin from a tin plating bath, in bath 70 the wire is again rinsed, at 90 the wire is periodically struck to cause it to vibrate and in bath 80 the wire is given a hot water rinse to cause it to dry quickly before winding. The wire is drawn off and wound at 16. Thereafter the wire may be drawn down to a diameter of .011" in twelve steps.

It will be seen that the invention provides a process and apparatus which, although it is directly contrary to the teachings of the prior art, provides unusual and unexpected advantages and a superior product.

We claim:

1. In an apparatus for electroplating wire, the combination comprising a series of baths including an electroplating bath horizontally arranged in substantially the same horizontal plane, a die adjacent a first end of said series of baths, means for feeding wire to said die, said die being of smaller size than said wire whereby said die is adapted to resist movement of the wire therethrough, means adjacent the other end of said series of baths adapted to apply sufficient tension to the wire to draw said wire through said die, the horizontal path between said die and said wire drawing means being substantially unobstructed whereby the wire passing in said unobstructed path is electroplated while under a substantially uniform drawing tension, said baths having parallel slits at the ends thereof for the passage of said wire therethrough and means adjacent one of said baths of said series adapted to set the wire to vibrating in the direction of the slits in said baths under the natural vibration frequency determined by the tension on the wire and the distance between said die and said drawing means whereby said vibrations extend along the entire horizontal path between the die and the drawing means.

2. The apparatus as set forth in claim 1 in which the said means for setting the wire in vibration comprises at least one finger for periodically striking said wire.

3. In a method of electroplating wire, the steps comprising continuously passing said wire to a drawing die of smaller diameter than said wire so that the said die is adapted to hold the wire to permit the wire passing therethrough to be tensioned sufficiently to reduce the size thereof, applying sufficient tension to the wire coming from said die to reduce the size thereof, said tension being applied at the end of a substantially unobstructed, straight, horizontally-spaced path from said die, continuously electroplating said wire while under said tension and while traveling in said unobstructed path, and maintaining the wire in substantially continuous vibration by intermittently striking the wire to cause it to vibrate all along said substantially unobstructed path at the natural vibration frequency of the wire as determined by length and the high tension of drawing of the wire.
